UNITED STATES PATENT OFFICE.

WILLIAM B. REYNOLDS AND WILLIAM ERNEST JACKSON, OF FORT WORTH, TEXAS,
ASSIGNORS OF ONE-TENTH TO SUSANNA MORGAN, OF GREENVILLE, TEXAS.

PAPER CUTTER.

Application filed April 2, 1925. Serial No. 20,063.

Our invention relates to paper cutters and more particularly to cutters for cutting off sheets of any required length from paper fed from rolls of paper; and the object is to provide a simple mechanism which will be convenient and easily operated and which will automatically return to inoperative position after a cutting operation. Other objects and advantages will be fully explained in the following description and the invention will be more particularly pointed out in the claims.

Reference is had to the accompanying drawings which form a part of this application.

Fig. 1 is a front elevation of the paper cutter. Fig. 2 is a side elevation of the same. Fig. 3 is a perspective view of the cutter and the guide therefor. Fig. 4 is a detail view of the paper guide and holding rollers.

Similar characters of reference are used to indicate the same parts throughout the several views.

The paper cutter is provided with a platform 1 which is supported on upright frame members 2 which are provided with cross-beam braces 3. The cutter consists of a rectangular frame 4 and a small wire or cord 5 which is held taut by the frame 4. The cutter is adapted to move vertically and a slot 6 is made in the platform 1 for the passage of the wire 5. A guide is provided for the frame 4 and this guide consists of two uprights 7 which are mounted in the platform 1 and attached to cross-braces 9 and provided with slots 8 for movement of the frame 4. The frame 4 is held in the elevated position by weights 10 to which are attached cords 11 which are extended upwardly and over idle pulleys 12 and then extended downwardly attached to the upper side of the frame 4. The pulleys 12 are mounted in the upper ends of uprights 7.

For the cutting operation, a foot lever 13 is fulcrumed on a cross-beam 3 and a cord 14 is attached to the lever 13 and extended upwardly over an idle pulley 16 which is mounted on a cross-beam 15. The cord 14 is then extended downwardly and run under an idle pulley 17 which is mounted on the cross-beam 9 and the cord 14 is then extended upwardly and attached to the lower side of the frame 4. The paper to be cut is mounted on rolls 18 which are journaled in suitable

bearings 19 which are attached to the uprights 2. Different rolls are provided for different widths of paper. The paper to be cut is drawn across the platform and over the slot 6 and in passing over the platform 1, the paper passes between small rollers 20 and 21 which serve as guides and also as holders. The upper roller 20 is held yielding against the paper by springs 22. Different pairs of rollers 20 and 21 are provided for paper of different widths. The rollers 20 and 21 will hold the paper with sufficient friction to prevent the paper from falling back from the back part of the platform after a portion of paper is cut from the sheet.

The opening through the platform for the cutter may be made wide and adjustable bars 23 provided for attachment to the platform at different adjustments. The bars 23 are spaced apart to form the slot 6. In this manner the slot 6 can be adjusted to the proper place to let the cutter 5 pass freely therethrough.

In operation, a sheet of paper is drawn over the top of the platform and across the slot 6 to obtain the required length of paper. The lever 13 is then pressed down by the foot to cause the cutter 5 to cut the sheet of paper.

What we claim, is,—

1. A paper cutter comprising a platform and a frame therefor, said platform having passage ways for a cutter, means for positioning paper to be drawn across said platform, a cutter movable vertically through said platform, a guide for said cutter in its vertical movements, a foot lever operatively connected to said cutter for moving the cutter downwardly, and means for automatically returning the cutter to inoperative position consisting of idlers journaled in the top of said guide, cords attached to said cutter and extended over said idlers, and weights attached to said cords.

2. A paper cutter comprising a platform having a slot therethrough for a cutter, a frame for said platform, a cutter movable through said slot, a guide for said cutter rigid with said frame, a foot lever operatively connected with said cutter for forcing said cutter down through said platform, and means for automatically returning the cutter to inoperative position consisting of idlers journaled in the top of said guide, cords attached to said cutter and extended over

said idlers, and weights attached to said cords.

3. A paper cutter comprising a platform having a slot therethrough for a cutter, a cutter movable through said slot, a guide for said cutter rigid with said platform, a foot lever and a cord attached to said foot lever and operatively connected to said cutter for forcing said cutter downwardly through said platform, and weights, idlers journaled in the top of said guides and cords attached to said weights and extended over said idlers and operatively connected to said cutter for automatically returning the cutter to inoperative position.

4. A paper cutter comprising a platform having passage ways for a cutter, a cutter

and a frame therefor movable through said passage ways, guides for said frame, means for positioning paper to be drawn across said platform, a foot lever and a cord attached to the foot lever and operatively connected to said frame for forcing said cutter downwardly, and weights, idlers journaled in the top of said guides and cords attached to said weights and extended over said idlers and operatively connected to said frame for automatically returning said cutter to inoperative position.

In testimony whereof, we set our hands, 30
this 27th day of March, 1925.

WILLIAM B. REYNOLDS.

WILLIAM ERNEST JACKSON.
